UNITED STATES PATENT OFFICE

WILLIAM F. PUNTE, OF PASSAIC, NEW JERSEY, ASSIGNOR TO CONTINENTAL CAN COMPANY, INC., OF NEW YORK, N. Y., A CORPORATION OF NEW YORK

COMBINED SHIPPING AND DISPLAY CONTAINER

Application filed March 16, 1929. Serial No. 347,670.

The invention relates to new and useful improvements in a combined shipping and display container.

An object of the invention is to provide a metal container having a top end provided with an opening, a cover seat about said opening, an inner fragile closure covering said opening, and a metal cover adapted to frictionally engage said seat for closing the opening, with a similar cover seat in the bottom end of the container for receiving and storing the cover when removed to display the contents through said fragile closure.

15 In the drawings:—

Fig. 1 is a view partly in side elevation and partly in vertical section showing a container embodying the improvement.

Fig. 2 is a view on an enlarged scale showing in vertical section a portion of the container with the cover in place for shipment.

Fig. 3 is a view similar to Fig. 2 with the cover removed and stored at the bottom of the container for displaying the contents 25 of the container.

The invention is directed to a metal container which may be used for packing food products, which container is so constructed that it may be readily shipped without danger of being broken and which may be uncovered for display purposes without rendering the contents of the container accessible unless the seal of the container is broken. This is accomplished by providing 30 the container body with a metal closing end at the bottom thereof and a metal top end having an opening therethrough. Associated with this top end is a fragile disc of any suitable material which is placed on the 35 inside of the container and secured by the double seam which joins the top end to the container body.

Extending about the opening is a seat for the metal cover and the metal cover is so 45 constructed as to frictionally engage said seat and thus close the container for shipment. The metal cover may be readily removed and the contents of the container viewed through the fragile closure which is 50 preferably transparent and at the same time

the contents are not rendered accessible unless the fragile closure be broken.

The bottom end of the container is provided with a cover seat which is similar to the cover seat in the top end and when the 55 metal cover is removed for displaying the contents of the container it is seated on the cover seat at the bottom end of the container. Thus it is that the metal cover is stored and becomes a unit with the package 60 during display.

Referring more in detail to the drawings, the improved container includes a body portion 1 preferably of metal and of any desired cross sectional shape. A bottom end 65 2 is secured to the body portion by a double seam 3. A top end 4 having an opening 5 is secured to the body portion by a double seam 6. The opening 5 is closed by a fragile disc 7 which is placed within the container 70 on the under face of the blank forming the top portion and rolled into the double seam with the top end. This fragile disc makes contact with the under face of the top end and is supported thereby. The top end is 75 formed with a cover seat 8 and a metal cover 9 is provided with a vertical wall 10 adapted to frictionally engage the cover seat 8 and thus hold the metal cover in place on the container. The cover is also provided with a portion 11 which overlies the double seam preferably to such an extent that it may be readily pried off.

The end of the container having the fragile closure is attached to the container 85 body by the manufacturer of the container and the cover is seated. The container thus formed is delivered to the packer who fills it with the goods desired to be shipped therein, after which the metal end 2 is secured to the container body by the usual double seaming operation.

The bottom end 2 of the container is formed with a depression 12 which provides a cover seat 13. The cover 9 when removed 95 from the container is placed in engagement with this seat 13 and will be frictionally held thereon. The seat 13 and the seat 8 are similar in construction. Thus it is that the metal cover may be secured to the con- 100

tainer forming a unit therewith, while the top end of the container is open so as to display the contents of the container through the transparent fragile closure therefor.

5 The container is filled with the desired goods for shipment. The bottom end 2 is secured to the container and it is thus shipped to the distributor. The distributor desiring to exhibit the contents of the container removes the metal cover from the top end and places it on the friction seat at the bottom end of the container thus securing the cover to the container. The contents are displayed and when the package is sold 15 the cover is always present ready for closing the package for delivery.

It is obvious that the manner of attaching the metal cover to the container may be varied without departing from the spirit of 20 the invention, the essential feature consisting in the capability of storing the cover by attachment to the container body in such a way that the contents of the container may at the same time be displayed.

25 Having fully described my invention, what I claim as new and desire to secure by Letters Patent, is:—

1. A combination shipping and display container including a body portion, a top 30 end secured thereto having a central depression and an opening therethrough forming a friction seat centrally of the depressed portion, said opening being so spaced inwardly from the wall of the depression as 35 to form a surrounding ledge at the base of said depression, a transparent fragile closure for said container located within said container and in contact with said top portion, a metal cover adapted to fit 40 within the frictional seat and held from contact with the fragile closure by the ledge at the base of the seat, and a bottom end secured to the body portion, said bottom end having in its outer face a similar cover 45 seat for securely holding and storing the cover when removed from the transparent closure for displaying the contents of the container.

2. A combination shipping and display 50 container including a body portion, a top end secured thereto by a double seam having a central depression and an opening therethrough forming a friction seat centrally of the depressed portion, said opening being so spaced inwardly from the wall 55 of the depression as to form a surrounding ledge at the base of said depression, a transparent fragile closure at the inner face of said top end and secured to the body portion by a double seam and in contact with said top portion, a metal cover adapted to fit within the frictional seat and held from contact with the fragile closure by the ledge 60 at the base of the seat, and a bottom end double seam secured to the body portion,

said bottom end having in its outer face a similar cover seat for securely holding and storing the cover when removed from the transparent closure for displaying the contents of the container.

70 In testimony whereof, I affix my signature.

WILLIAM F. PUNTE.
